UNITED STATES PATENT OFFICE.

ARTHUR KRAUSE, OF WOODHAVEN, NEW YORK, ASSIGNOR TO LION ELECTRIC MANUFACTURING COMPANY, INC., A CORPORATION OF NEW YORK.

DESIGN FOR A CHANDELIER.

Application filed October 4, 1927. Serial No. 23,627. Term of patent 7 years.

To all whom it may concern:

Be it known that I, ARTHUR KRAUSE, a citizen of the United States, and residing at Woodhaven, in the county of Queens and State of New York, have invented a new, original, and ornamental Design for a Chandelier, of which the following is a specification, reference being had to the accompanying drawings, forming part hereof.

The figure is a perspective view of the chandelier embodying my design.

I claim:

The ornamental design for a chandelier as shown.

ARTHUR KRAUSE.
